UNITED STATES PATENT OFFICE

TRIAN BERBECK, OF BALTIMORE, MARYLAND

AIRPLANE

Application filed October 28, 1930. Serial No. 481,790.

This application is a continuation in part of my copending application Serial No. 422,-639, filed January 22, 1930.

This invention relates to improvements in airplanes and more particularly has reference to a method and means for increasing the lift factor of airfoils.

A considerable effort has been expended to increase the lift effect on airplane wings as its desirability has long been recognized. At the present, the advantage to be gained from a short distance take-off and a relatively low landing speed, so that the plane may land in small spaces, are still being sought. Methods proposed to secure these advantages have been an increased wing camber and an increased wing area. However, these expedients are limited by the size of the wings which are capable of being used. Other methods have proposed a wing construction which allows the camber and the wing area to be altered at will. While this latter type of construction is correct in theory, it is nevertheless impractical because of the many mechanical parts required by it.

Besides these practices mentioned above, attempts have been made to increase the lifting power of an airfoil by increasing the air current velocity over the top surface. Along these lines the slotted wing has had considerable success, but as yet it is not suitable in all instances. Also among this latter type of methods for increasing the lift of airfoils is the use of blowers adapted to direct a stream of air over the upper surface of the plane. These have been unsuccessful due to the fact of a small increase of velocity obtained for the great amount of weight added to the plane.

It is the major object of this invention to provide a method for increasing the lift of airfoils and means for carrying the same into effect which lack the inherent defects of methods and constructions now in present practice.

An equally important object of the invention is to create a current of air which is directed around the airfoil from its bottom surface upwardly and over the top surface thereof.

Another object of the invention is to make

use of the interior surfaces of an airfoil to increase the lifting effect.

Yet another object of the invention is to circulate a current of air within the interior of an airfoil, the air current entering and leaving the airfoil at its bottom surface.

In addition to the above objects, the present invention contemplates the construction of airplane wings so that an airplane may land in small spaces, at relatively low speeds and with a maximum factor of safety.

Still another object of this invention is the provision of a hollow airfoil having a rotatable impeller mounted within openings formed in the lower surface thereof, and having openings or slots formed in the upper surface thereof.

A still further object of this invention is the association with the wings of an airplane of means operable for increasing the lift effect of the airfoils during descent of the airplane.

With these and other objects in view, which may be incident to my improvements, the invention consists in the parts and combinations to be hereinafter set forth and claimed, with the understanding that the several necessary elements comprising my invention may be varied in construction, proportions and arrangement without departing from the spirit and scope of the appended claims.

The present invention comprehends a method and apparatus for increasing the lift factor of airfoils. One method of practically effecting the concept of the invention is the provision of an airfoil having an opening formed in its lower surface and means upon the plane with which the airfoil is associated for rotating vane mechanism positioned within the openings.

It is also within the concept of the present invention to so position openings in the hollow wings or airfoil structures equipped with the rotating impellers, that the impellers may be caused to rotate due to the passage of air currents through the wings or airfoil sections.

In order to make my invention more clearly understood, I have shown, in the accompanying drawings, means for carrying the

same into practical effect without limiting the improvements in their useful applications to the particular constructions which, for the purpose of explanation, have been 5 made the subject of illustration.

In the drawings there is illustrated a dia-grammatic representation of the application of the present invention in which:

Figure 1 is a horizontal bottom view of an 10 airplane showing the construction forming this invention embodied in the wing or air-foil of the plane.

Figure 2 is a partial vertical sectional view 15 of an airplane provided with an auxiliary airfoil having the impeller structure embodied therein.

Figure 3 is a top plan view of one form 20 of airfoil constructed in accordance with the present invention, being taken on line 3-3 of Figure 2.

Figure 4 is a vertical sectional view taken on line 4-4 of Figure 2.

Figure 5 is a view similar to Figure 3, illus-25 trating a modification of the present invention.

Figure 6 is a vertical sectional view of a still further modification of the present in-vention.

There is shown in Figure 1 an airplane 30 having a fuselage 1 and a wing or airfoil 2. The airfoil 2 is provided with the usual ailerons 3 while the tail of the fuselage has the conventional elevators 4 and stabilizer 5. A suitable tail skid 6 and landing gear 7 are also shown.

As may be observed from Figure 1, the wing 2 is of any suitable airfoil section and has formed upon its under surface a plurality of openings 9. The openings 9 are formed 40 in each semi-span of the wing and have positioned therein rotatable vane elements 10 which are fixed to the shafts 11. The shafts 11, as shown in Figure 4, are rotatably mounted in suitable bearings 12 which may 45 be fixed to the ribs 13 of the airfoil. How-ever, any other suitable bearing support for the shafts 11 may be employed. This construction, it will be observed, provides a set of vane elements on each side of the fuselage 50 or on each semi-span.

For the purpose of providing a commercial structure, the openings have been shown as formed within a plate like structure 9'. A plate 9' is mounted upon each semi-span of 55 the airfoil and is covered with the usual sur-facing material. It will be appreciated that by this feature, the plate may be made espe-cially and set in or recessed into the lower 60 wing surface so that it is flush thereto. Of course, if it is desired, the openings 9 may be cut directly into the lower wing surface and the plate 9' dispensed with.

It is to be noted that each vane element is 65 of a size substantially equal to an opening 9, and is so designed that it may freely rotate

within the opening. Likewise it should be noted that each vane element is constructed in such a manner that when in position to close its opening, its bottom surface will be substantially flush with the bottom surface 70 of the airfoil.

For rotating the vanes a suitable power unit 14, shown by the dotted lines in Figure 1, is connected to the shafts 11. In order to prevent the drawings from becoming highly 75 complicated by reason of unnecessary detail, the shafts 11, provided for each set of vane elements, have been shown as directly connected to the power unit 14. It is to be understood, however, that a suitable clutch ar-rangement between each of these shafts and the power source may be employed so that either or both shafts 11 may be uncoupled from the power unit and the latter may be actuated without rotating the vane 85 elements. Also it is to be understood that although I have shown a separate power unit for rotating the vane elements, by suitable connections the shafts 11 could be en-gaged with the motor driving the propeller 8 90 and the separate power source 14 eliminated.

While the construction details have shown each set of vane elements as being positioned upon the wing so that the axis of the shaft upon which the vanes are mounted is parallel 95 to the longitudinal axis of the airfoil, it will be appreciated that each set of vanes may be so positioned that the axis of its shaft is per-pendicular to the longitudinal axis of the air-foil or it may be angularly disposed thereto. 100 In these latter events, each set of vane elements could be driven by a separate power unit or by means of suitable gearing could be connected to a centralized unit, such as that shown at 14, or to the prime mover rotating 105 the propeller.

As it will hereinafter become apparent, the invention is in no ways limited to the num-ber of vane elements, it being within the 110 scope of the invention to employ one such vane element of greatly enlarged area on each semi-wing span. Neither are the vane ele-ments limited in shape, area or their position 115 with respect to either the longitudinal or the transverse axis of the airfoil. For instance, the vanes or impellers may be of any desired shape, circular, square, etc., and may be lo-cated in any portion of the wing structure, in any position depending upon the type of air-plane and the results to be obtained. More-over, while I have shown the invention as 120 embodied in a monoplane, it will be appre-ciated by those skilled in the art, that it may be embodied in other types of plane as well, for example, a biplane or triplane. It will 125 also become apparent that the invention is not limited to any particular type of airfoil sec-tion, as it may be equally well employed with any airfoil section design.

It has been pointed out as an object of the 130

invention to provide a method and means for increasing the lifting power of airfoils, this increased lift being of particular advantage in allowing a short distance take-off and a relatively low landing speed and small space for landing a plane. As is well known, the creation of lift in an airfoil is due to the pressure differential existing between the pressure upon the upper surface of the airfoil and the pressure upon its lower surface. The pressure upon the upper surface is negative in value, or a suction effect, while that upon the lower surface is positive with respect to the atmospheric pressure.

The best explanation of the values of these areas of high and low pressure about the airfoil may be obtained by the application of some of the theorems of hydro-dynamics, particularly Bernoulli's. As an airfoil is moved forwardly, there is always air ahead of it which has not been disturbed by the passage of the airfoil. This air is referred to as the air stream and as it reaches the airfoil divides, part of it going over the upper airfoil surface and part of it going below the airfoil surface. Bernoulli's theorem would indicate that the air nearest the upper surface of the wing, which is at a pressure less than that in the air at a distance from the wing, has a velocity which is higher than that in the air stream at a distance from the wing. On the other hand the velocity of the air nearest the lower wing surface is less than that of the air stream. By further application of this theorem, it will be appreciated that the pressure of the air passing over the airfoil is less than the pressure of the air below the airfoil. It is this pressure differential which creates lift.

To go into further detail, it is believed that such a condition as outlined above lies in the assumption that a circulation of air exists about the airfoil. From demonstrations and experiments it has been shown, as a fact, that when air starts to move past the airfoil, there is formed along the trailing edge a succession of small vortices which break off and remain in the air as the airfoil passes. These trailing edge vortices, it is assumed, set up a counter circulation around the wing which increases in strength until the flow off the trailing edge is smooth. This effect takes place within a comparatively small amount of time and the full lift of the airfoil is developed very quickly after the airfoil begins to move.

Assuming that an airfoil is positioned so that its leading edge is pointed towards the left as shown in Figure 2, such a counter circulation of air, as that described above, is directed in a clockwise direction. Now this counter air current, as it passes over the lower surface of the airfoil, will be opposite in direction to the air flowing over the lower surface caused by the movement of the airfoil, and hence will decrease its velocity with a consequent pressure rise. On the other hand,

as the counter current of air passes around the leading edge and over the upper surface of the airfoil, its direction will be coincident with that of the air flowing over this surface, and it will tend to add to or build up the velocity of this air with a consequent decrease in pressure upon the upper surface.

It is the purpose of this invention, among other objects as will be pointed out, to make use of this theory as outlined above and to build up or strengthen the counter air current. In order to accomplish this, the rotatable vanes such as have been shown, are employed. By rotating these vanes at a suitable speed, an additional counter current aiding that already mentioned will be generated, the vanes being rotated in a clockwise direction as shown in Figure 2.

As it will be noted in Figure 2, each vane element 10 is formed of a blade 10a and a blade 10b. In explanation of the operation of the device, the revolution of one of the blades will be traced. Assume that the blade 10a as shown in Figure 2, is in such position that it is flush with the right hand side of the opening 9.

Now as the blade 10a is rotated from the position described, it moves downwardly and its front face, that is, the face adjacent to the leading edge of the airfoil, is in contact with the air flowing over the lower airfoil surface. Besides increasing the pressure upon the lower surface, this results in deflecting some of this air stream into the interior of the airfoil and moreover creates a current or flow of air through the airfoil itself. As is well known, centrifugal force will cause the deflected and the generated air, caused by the rotation of the blade, to be given a considerable velocity as the blade 10a moves towards the leading edge and within the airfoil. This circulation of air within the airfoil is continued, and because of the shape of the airfoil itself and the continued rotation of the blade, will be swept through the interior and ejected or deflected through the right hand side of the opening 9 as the blade 10a again assumes its initial position.

It will be observed that the direction of this air current flowing through the airfoil is clockwise and the same as the counter current of air set up by the trailing edge vortices. As this air is ejected from the right of the openings 9, it is commingled with the circulatory counter current flowing around the airfoil and the velocity of the latter is built up due to the addition of the air expelled from within the airfoil as the blade descends.

The counter circulatory current of air flowing over the lower surface of the airfoil, it will be appreciated, has had its velocity considerably increased and as this meets the air stream flowing over the lower surface in an opposite direction to it, the velocity of the latter will be decreased. This results in an

increase of pressure upon the underside of the airfoil which exceeds the amount possible to be attained without the use of the vane elements.

5 Now as this circulatory counter current of increased velocity passes around the leading edge of the airfoil and over its upper surface, it is directed in a path substantially coincident with the air stream flowing over 70 the upper surface, and the velocity of this air stream is built up with a consequent greater restriction of pressure on the upper surface. Hence it will become apparent that by the use of the vane elements, as described, the 10 pressure upon the lower surface of the airfoil 75 will be considerably increased, while that upon the upper surface will be decreased. As it is apparent, the result of this enlarged pressure differential will create an increased lift 15 factor.

Besides generating an increased counter current having a circulatory flow around the airfoil, the invention intends to make use of the inner surfaces of the airfoil as well as the 20 outer surfaces for lifting effects. It has already been mentioned that an air current of considerable velocity is circulated through the interior of the airfoil due to the rotation of the blades forming each vane element. 25 The velocity and pressure of this air is not only due to that deflected from the lower air stream by reason of it impinging against each blade as it starts to ascend into the interior of the airfoil, but is also caused by air 30 current generated by the rotation of the vane elements. It has been conclusively proved that the upper surface of an airfoil is within an area of negative pressure and it will hence be realized that the pressure 35 created upon the interior of this surface, due to the vane elements, will be opposite in sign and sufficient to cause a considerable pressure differential to exist between the upper exterior surface of the airfoil and the upper 40 interior surface of the airfoil. As a consequence, an increased lift effect is provided for the airfoil and the interior surface as well as the exterior surface will be utilized.

It has been mentioned that the blade elements are rotated at a suitable speed. Such a speed is dependent upon such factors as the size of the airfoil, the area of the vanes, and also upon their number. While the vanes have been disclosed as being circular in shape, 55 it will be appreciated that any other geometrical shape desired may be given to them without departing from the spirit of the invention or the scope of the appended claims. Likewise, it will be appreciated that the invention is not limited to the number of blades formed upon each blade element. For instance, a single vane may be employed.

It will be appreciated that the invention is of great advantage in increasing the lift of an airplane, being particularly useful in tak-

ing off and landing. The power unit 14 is actuated so as to rotate the vane elements as described, with the result that a counter circulatory airflow and an airflow within the interior of the airfoil are set up. This will greatly increase the lift coefficient at all angles of attack, and hence will allow the plane to be taken off within a relatively small space and to be landed at relatively low speed and within a small area.

75 While the plane is flying and it is no longer desired to rotate the vane elements, the actuation of the power unit is arrested and the shafts 11 may be unclutched therefrom. It should be noted that either or both sets of vane elements may be unclutched from the power unit and hence either or both of them may be driven as desired.

80 If desired, the impellers may be locked in a position so as to maintain the same flush with the lower surface of the wing. The pressure of the air stream passing below the lower wing surfaces will act on the vanes in closed position, and the airfoil will function similar to any conventional wing. The reason for 85 constructing the vane elements so that when they are in closed position they are flush with the lower surface will now become apparent. By this construction, parasitic resistance due to their projection below the airfoil surface is 90 prevented. Although the bearings 14 have been shown as extending below the lower wing surface, it will be appreciated that these may be so constructed as to be substantially 95 flush therewith.

100 While the advantages derived from this construction have been outlined in connection with the landing and the taking off of airplanes, and are of particular value in these instances, it will be understood that they will be effective while the plane is flying in the air. Such a use of the vane element is of advantage in pulling an airplane out of a stall, a dive, or a spin.

105 As is well known, there exists upon the wing tips of an airplane, a whirl or vortex, which creates an uneven distribution of pressure over the wing surfaces near the tips, increases the drag of the airfoil and in general 110 decreases the stability of the airplane. Attempts have been made to ameliorate this condition by varying the shape of the wing tip. As a consequence, it has been discovered that an elliptical tipped wing gives the best results, but these are not highly satisfactory. 115 By suitably positioning a series of vane elements upon the wing tips, either as shown or so that the axis of rotation is perpendicular to the longitudinal plane axis or angularly disposed thereto, these air currents flowing 120 over and under the wing tips could be straightened out and hence an even distribution 125 of the pressure over this area would be procured with a decrease in the drag of the airfoil.

In Figure 2, the invention is embodied in an auxiliary airfoil adapted to be mounted below the main airfoil of an airplane, one such auxiliary airfoil being positioned on each semi-wing span. Here a cabin plane having a fuselage 1' and an airfoil 2' is provided with an auxiliary airfoil 15. The fuselage of the plane is provided with the usual wind shield and supporting structure therefor as indicated by the reference numeral 16.

Each auxiliary wing 15 is provided with a set of vane elements such as that described. These vane elements are actuated similarly to those shown in Figure 1. Under each semi-span of the main airfoil 2' the auxiliary wing is mounted by means of suitable supports or braces 17 which may be secured to the main airfoil 2' or to the fuselage itself to both of these structures.

Each auxiliary airfoil is positioned at such a distance below the main airfoil 2' that substantially no interference with the air current passing under the lower surface of the airfoil 2' is created. As is well known, such a distance is dependent upon the gap/cord ratio giving the best results and it may be decreased by positively staggering the airfoils.

In such construction, it will be appreciated that the main airfoil 2' may also be provided with vane elements such as shown in connection with the airfoil 2 in Figures 1 and 3.

By the structure employed in Figure 2, construction of biplanes or triplanes having a smaller wing area is permitted. Biplane and triplane construction is employed where it is found impractical, because of the wing area required, to embody an airplane design in a monoplane design. By the use of the auxiliary airfoils, it will be appreciated that the wing area of such a plane and consequently its weight, could be considerably reduced while its lift factor would be greatly increased. In the construction shown in Figure 2, it will be apparent that both the main wing 2' and the auxiliary wing 15 will function in a manner similar to that described in the embodiment of the invention disclosed in Figure 1.

Units such as an auxiliary airfoil 15 employing the present invention may be positioned at various points on the plane where an increased lift is desirable.

I have found that the present invention may be operated to increase the lift effect of an airplane while descending without employing power to effect rotation of the impeller elements 10. In the drawings, I have shown a form of invention in which the upper surface of the wing section 15, equipped with the rotatable impellers 10, is provided with a plurality of openings 18, so positioned in the upper surface of the airfoil as to effect rotation of the impellers 10 when they are free to rotate and when the stream of air is

flowing through the wings or auxiliary airfoil sections 15. If desired, as shown clearly in Figure 4, the openings 18 may be provided with suitable closures 19 carried by an actuating member 20 and controlled by the lever 21 for opening or closing the openings 18 any desired amount.

It will be appreciated that in order to effect the most efficient operation of the impellers 10 when they are not rotated by a source of power, they should be disconnected from the engine or other source of power. In Figure 4, I have shown one means of accomplishing this purpose. In that figure, the impellers 10 are carried on suitable hubs 22, rotatably mounted on the shaft 11. The hubs 27 are provided with splined sockets 23, into which may be moved an enlarged portion 24 of shaft 11, provided with splines adapted to cooperate with those in the socket 23 to cause the impellers 10 to rotate with the shaft 11. Thus when it is desired to cause an airplane to descend without the use of a source of power for rotating the impellers 10, the lever 25 may be actuated to cause the shaft 11 carrying the enlarged splined portions 24 to become disengaged with the impellers 10, thereby permitting the same to be freely rotated within the airfoil section 15.

When an airplane equipped with the present invention is descending, there is a flow of air through the wings which may be caused by a principle analogous to that employed in the provision of the so-called slotted wing. This current of air will cause rotation of the impeller 10, and this rotation of the impeller will have a tendency to increase the lift effect of the airfoil equipped with the same in a manner similar to that hereinbefore described. In place of the location of a plurality of small openings in the upper surface of a wing section constructed in accordance with the present invention, one or more slots may be provided in the forward portion of the upper surface of the wing, as shown in Figure 5. In this figure, a single slot 26 is shown located in the upper forward portion of the wing section. Means similar to the closure operators shown in Figure 4 may be associated with the slot to close the same or open the same to any desired degree. This form of invention operates similarly to the form just described. The lift may be varied by varying the openings.

If desired, the present invention may be further modified by locating the shaft 11 more centrally within the airfoil section as shown in Figure 6. In this figure, the shaft 11 is positioned above the lower surface of the airfoil and thereby will have a slightly different effect on the lift of the airfoil section. In some instances, it will be found that this form of the invention will operate more satisfactorily than the form shown in the other figures and vice versa.

It may be possible that the lift effect obtained by the present invention is due to the pressure created by centrifugal action of the vanes or impellers, which exerts a pressure 5 upwardly against the interior of the wing surface and also in a general opposite direction. On the other hand, it may be possible that the invention operates on the principle employed in the so-called rotor ship.

10 Regardless of any theory of operation, experiments have shown that an increased lift effect is obtained when airfoils are constructed and operated as herein described.

Having described the features and operation 15 of the device, it will be appreciated from the foregoing description that I have provided a method and means for greatly increasing the lifting powers of airfoils. Such construction as that disclosed will allow a 20 short distance take-off for a plane and a relatively small landing area besides having many other advantageous effects which result from the benefit of increasing the lift of airfoils.

25 While I have shown and described the preferred embodiment of my invention, I wish it to be understood that I do not confine myself to the precise details of construction herein set forth, by way of illustration, as it is apparent 30 that many changes and variations may be made therein, by those skilled in the art, without departing from the spirit of the invention, or exceeding the scope of the appended claims.

35 I claim:

1. An airfoil having an opening in its lower surface, an opening in its upper surface, an impeller rotatably mounted within the opening formed in the lower surface of 40 the airfoil, and closure means associated with the opening in the upper surface of the airfoil.

2. An airfoil having an opening in its lower surface, an impeller rotatably mounted within said opening, said airfoil having a slot in its upper surface adapted to increase the lift effect of the airfoil, and a closure for 45 said slot.

3. An airfoil having a plurality of openings formed in its lower surface and a plurality of impellers rotatably mounted within said openings, said airfoil also having openings in its upper surface adapted to direct air streams through said airfoil to rotate the impellers and thereby increase the lift effect 55 of the airfoil and means for adjusting the size of the openings in the upper surface of the airfoil.

4. An airfoil having a plurality of openings formed in its lower surface and a plurality of impellers rotatably mounted within said openings, said airfoil also having a slot in its upper surface adapted to direct air streams through said airfoil to rotate the impellers and thereby increase the lift effect 60

of the airfoil and means associated with the slot in the upper surface of the airfoil to control the amount of air flowing through the slot, and thereby control the rate of rotation 70 of the impellers.

5. An airfoil having a plurality of openings formed in its lower surface, disk-like impellers rotatably mounted within said openings, each of said impellers being so constructed that when it is in a position to close the opening within which it is mounted, it will lie substantially flush with the surfacing material of the airfoil, said airfoil also having an opening formed in its upper surface adapted to cooperate with said impeller to effect a variation in the lift of the airfoil. 80

6. An airfoil having a recess formed in its lower surface, a shaft extending through said recess, a disk-like impeller mounted upon said shaft and positioned within said recess, means detachably connected to said shaft for rotating it and said impeller, and said airfoil also having openings formed in the upper surface thereof adapted to cooperate with the impeller to increase the lift effect of said 90 airfoil.

7. An auxiliary airfoil for an airplane adapted to be mounted below a wing of said airplane, said auxiliary airfoil being provided with a plurality of openings upon its lower surface, vane elements rotatably mounted within said openings, said vane elements being so constructed as to lie substantially flush with the lower surface of 95 said auxiliary airfoil when the vane elements are in position to close said openings, said airfoil having an opening formed in the upper surface thereof adapted to cooperate with the vane elements to increase the lift effect on the airfoil. 100

8. In an airplane an auxiliary wing therefor adapted to be positioned below a main wing, said auxiliary wing having an airfoil section and provided with an opening upon its bottom surface, an impeller rotatably mounted within said opening, and power driven means upon the airplane for rotating said impeller, said airfoil having an opening formed in the upper surface thereof adapted to cooperate with the vane elements to increase the lift effect on the airfoil and means associated with the openings in the upper surface of the airfoil for varying the effective area thereof. 110

9. A wing for an airplane having an airfoil section of hollow construction covered with surfacing material, an opening formed in the bottom surface of the material, an impeller rotatably mounted within said opening, said material having openings formed therein in the upper surface thereof, said last mentioned openings being so positioned as to effect rotation of the impeller to increase the lift effect of the wing and means associated with the openings in the upper surface 115 120 125 130

of the airfoil for varying the effective area thereof.

10. An airfoil of hollow construction covered with surfacing material, said material having an opening formed in the lower surface of the airfoil, a shaft positioned within the airfoil a distance from the surfacing material, an impeller mounted upon said shaft, and means for detachably connecting said shaft with a source of power, said surfacing material also having an opening formed in the upper portion of the airfoil adapted to effect the flow of a stream of air through the airfoil and rotate the impeller when disconnected from the source of power.

11. In an airplane a plurality of auxiliary airfoils therefor, said auxiliary airfoils adapted to be mounted below the main airfoil of said airplane, each of said auxiliary airfoils being provided with a plurality of openings formed upon their bottom surface, vane elements rotatably mounted within each of said elements, said airfoils having an opening formed in the upper surface thereof adapted to cooperate with the vane elements to increase the lift effect on the airfoil, and means associated with the openings in the upper surface of the airfoils for varying the effective area thereof.

12. An airfoil of hollow construction covered with surfacing material, said material having an opening formed in the lower surface of the airfoil, a shaft positioned within the airfoil a distance from the surfacing material, an impeller mounted upon said shaft, and means for detachably connecting said shaft with a source of power, said surfacing material also having an opening formed in the upper portion of the airfoil adapted to effect the flow of a stream of air through the airfoil and rotate the impeller when disconnected from the source of power, and means associated with the openings in the upper surface of the airfoils for varying the effective area thereof.

In testimony whereof I affix my signature.
TRIAN BERBECK.
